UNITED STATES PATENT OFFICE.

WILLIAM G. KENDALL, OF NEWARK, NEW JERSEY.

POWDER-PUFF.

1,374,746.

Specification of Letters Patent. Patented Apr. 12, 1921.

Application filed November 4, 1920. Serial No. 421,765.

To all whom it may concern:

Be it known that I, WILLIAM G. KENDALL, a citizen of the United States, and a resident of Newark, in the county of Essex 5 and State of New Jersey, have invented a new and Improved Powder-Puff, of which the following is a full, clear, and exact description.

The object of the invention is to provide 10 a new and improved powder puff, which is simple and durable in construction and cheap to manufacture.

Another object is to permit of quickly and accurately assembling the parts without 15 resorting to sewing or requiring highly skilled labor.

Another object is to firmly fasten the body parts of powder puff material in stretched position without danger of the 20 body parts becoming detached or loosened.

With these and other objects in view, the invention consists of certain novel features of construction as hereinafter shown and described and then specifically pointed out 25 in the claims.

A practical embodiment of the invention is represented in the accompanying drawings forming a part of this specification, in which similar characters of reference indicate corresponding parts in all the views. 30

Figure 1 is a perspective view of the improved powder puff;

Fig. 2 is a plan view of one of the body parts with the padding and carrier ring superimposed thereon and the handle fastened in position;

Fig. 3 is a cross section of the same on the line 3—3 of Fig. 2;

Fig. 4 is a plan view of the other body part with its padding and carrier ring superimposed thereon;

Fig. 5 is an enlarged cross section of the powder puff with the several members in partly assembled position; and

Fig. 6 is a similar view of a portion of the finished powder puff.

The powder puff in its general construction comprises two interlocked rings 10 and 11, preferably of sheet metal, and over 50 which are stretched the body parts 12 and 13, preferably both of powder puff material such as pile fabrics, flannel, felt and the like. A handle 14 in the form of a ribbon or a band extends across the outer face of 55 the body part 12 and its ends are attached to pins or points 15 struck up on the inner

edge of the ring 10 and located diametrically opposite each other. Paddings or fillings 16 and 17 of cotton batting or other soft material are preferably interposed between 60 the rings 10 and 11 and their body parts 12 and 13 so as to give the desired cushioning effect to the said body parts at the time the puff is used in the usual manner.

The ring 10 is provided with locking arms 65 20 struck up from the inner edge of the ring 10, and the other ring 11 is provided with an annular inturned spacing and clamping rim 21 interlocked with the arms 20 so as to fasten the two rings together. The body 70 part 12 has its peripheral portion scalloped and folded over the rim and clamped in place between the rim 21 and its ring 11 by the arms 20. The other body part 13 has its peripheral portion folded over the 75 peripheral edge of the ring 10 and clamped in place on the inner face of the ring by the rim 21, as will be readily understood by reference to Fig. 6. In practice, the parts 22 and 23 are preferably scalloped to avoid 80 undue bulkiness. It is understood that by this arrangement adjacent scallops are prevented from overlapping.

By reference to Fig. 2 it will be noticed 85 that the points 15 are located between adjacent arms 20, and the scallops on the flange 22 correspond in number to the arms 20, but in assembling the parts the ring 10 is superimposed on the body part 12 and so positioned that the points 15 are in alinement 90 with two oppositely disposed scallops, and these two scallops are turned in and engage with the points 15, after which the ends of the handle 14 are turned inward and likewise engaged with the points 15. The remaining scallops are folded inward and pass between the corresponding adjacent pairs of arms 20 without overlapping one the other. It will be noticed that by the arrangement described the ring 10 can be 100 readily positioned relative to the body part 12 and the ribbon 14 when assembling the parts. It is understood that the ring 10, the handle 14 and the padding 16 are positioned one relative to the other, as shown 105 in Figs. 2 and 3, and the body part 13 and the padding 17 are positioned one relative to the other, as shown in Fig. 4. When this has been done, the two structures or sections are superimposed with the rings opposite 110 each other (see Fig. 5) and placed in a press to interlock the arms 20 with the rim 21 to

fasten the several members of the powder puff together, as shown in Fig. 6. It is understood that when the two structures are assembled, as shown in Fig. 5, the arms 20 have their upper ends in close proximity to the under side of the inner edge of the ring 11 with the flange 23 of the body part 12 interposed between the ring 11 and the said arms 20. On pressing the rings toward each other 10 in the press the arms 20 are bent outward between the ring 11 and its rim 21, and the latter moves into engagement with the flange 22 of the body member 12 extending over the inner face of the ring 10. Thus the 15 two rings are interlocked and at the same time the flanges 22 and 23 are firmly clamped in position between the two rings.

The spacing and clamping rim 21 of the ring 11 is approximately S-shaped in cross 20 section and it serves to hold the rings 10 and 11 and the body parts 12 and 13 spaced apart to give the desired fullness to the powder puff, thereby avoiding a flat appearance. It will also be noticed that the locking arms 25 20 of the ring 10 pass into the rim 21 to unite the rings and to clamp the flange 23 of the body part 13 in place on the ring 11. Furthermore, the free edge of the rim 21 engages the flange 22 of the body part 12 30 and clamps the same against its ring 10 thus securely fastening this body part to its ring 10.

The powder puff shown and described comprises but few parts which can be readily 35 assembled and quickly fastened together without requiring highly skilled labor. It will further be noticed that the powder puff is very simple and durable in construction and its parts are not liable to become detached or loose.

Having thus described my invention, I claim as new and desire to secure by Letters Patent:

1. As an article of manufacture, a powder 45 puff comprising two superposed rings provided with interlocking members, one of the said rings having points located diametrically opposite each other, two textile body parts stretched over the outer faces of the 50 said rings and having their peripheral portions extending over and between the rings,

the said interlocking members clamping the said peripheral portions in place between the rings, and a handle formed of a piece of ribbon attached at its ends to the said ring 55 points and extending across the outer surface of the body part stretched over the ring.

2. As an article of manufacture, a powder puff comprising two superposed rings, one of said rings having an inturned spacing and 60 clamping rim and the other having struck-up locking arms interlocked with the said rim and two body parts of powder puff material having their peripheral portions in-turned and clamped between the said rings. 65

3. As an article of manufacture, a powder puff comprising two superposed rings, one of said rings having an inturned spacing and clamping rim and the other having struck-up locking arms interlocked with the 70 said rim, two body parts of powder puff material having their peripheral portions in-turned and clamped between said rings and a padding interposed between each of the 75 said rings and its body part.

4. As an article of manufacture, a powder puff comprising two superposed rings, one of said rings having an inturned spacing and clamping rim and the other having struck-up arms for interlocking engagement 80 with the said rim, one of said rings having struck-up points located approximately diametrically opposite each other, two body parts of powder puff material having their peripheral portions in-turned and clamped between said rings, a handle formed of a piece of ribbon attached at its ends to the 85 said points and extending across the outer face of one of the body parts, and a padding interposed between the said rings and the 90 corresponding body parts.

5. As an article of manufacture, a powder puff comprising two superposed rings, one of the rings having an integral spacing and clamping rim approximately S-shaped in 95 cross section, the other ring having locking arms bent into engagement with the said rim, and two body parts of powder puff material having their peripheral portions in-turned extending between the rings and 100 clamped in place thereby.

WILLIAM G. KENDALL.
